FIG. 1 is a top perspective view of a range hood;
FIG. 2 is a bottom perspective view of a range hood of FIG. 1;
FIG. 3 is a top view of a range hood of FIG. 1;
FIG. 4 is a front view of a range hood of FIG. 1;
FIG. 5 is a side view of a range hood of FIG. 1;
FIG. 6 is a rear view of a range hood of FIG. 1; and,
FIG. 7 is a bottom view of a range hood of FIG. 1.
The features shown in broken lines depict environmental subject matter only and form no part of the claimed design.
